UNITED STATES PATENT OFFICE.

JOSEPH W. LEWIS, OF PHILADELPHIA, PENNSYLVANIA, ASSIGNOR TO THE ATLANTIC REFINING COMPANY, OF PHILADELPHIA, PENNSYLVANIA, A CORPORATION OF PENNSYLVANIA.

PETROLEUM-TREATING APPARATUS.

Original application filed April 19, 1917, Serial No. 163,171. Divided and this application filed October 28, 1920. Serial No. 420,126.

To all whom it may concern:

Be it known that I, JOSEPH W. LEWIS, a citizen of the United States, residing in the city and county of Philadelphia, State of Pennsylvania, have invented certain new and useful Improvements in Petroleum-Treating Apparatus, of which the following is a specification.

My invention relates to apparatus for 10 treating petroleum, petroleum distillate or petroleum residuum in any suitable way for obtaining petroleum products in general, and particularly for producing light hydrocarbons from heavier oil.

My invention resides in structure for condensing oil vapors, and is of such nature, as hereinafter more particularly described, as to effect, preferably by air cooling, condensation of oil vapors delivered thereto, 20 and more particularly to effect partial condensation of the oil vapors delivered thereto, leaving some of the oil vapors uncondensed for delivery to a point beyond the condensing structure.

My invention resides in oil vapor condensing structure of the character herein-after described.

This application is a division from my 30 application Serial Number 287,178, filed April 3, 1919, which latter is in turn a division from my application Serial Number 163,171, filed April 19, 1917, which has matured into Letters Patent No. 1,364,443.

For an illustration of one of the various 35 forms my invention may take, reference may be had to the accompanying drawings, in which:

Fig. 1 is a side elevational view, partly in section, of the condenser structure and part 40 of an associated still structure.

Fig. 2 is a view at right angles to the view in Fig. 1 of structure shown therein.

Fig. 3 is a fragmentary view of part of the structure of Fig. 1 as seen from a direction at right angles thereto.

Figs. 4 and 5 are sectional views, partly in plan, taken on the lines 4-4 and 5-5 of Fig. 2.

Referring to the drawing, S represents a vertical still upon whose upper end, preferably high in the air, is carried the condenser

structure. The still may be provided with a manhole 1.

Within the still S exist or are produced oil vapors, generally those of oils of different boiling or condensation points. These vapors are led off from the still S through the vapor outlet pipe 20 communicating through valve 21 with a sweat-out line or pipe 22, and with the pipe 23 leading to the 60 safety valve 24 whose discharge side communicates with a vertically extending pipe 25. The main vapor line or pipe 20 communicates also through the valve 26 with the upwardly and then downwardly extending vapor line or pipe 27, which communicates with the initial header 28 of the aerial or air condenser. The header 28 communicates with a plurality of transversely extending initial manifolds 29 with which communicate the 70 numerous smaller vertically extending pipes 30 connected in various groups through the top connecting pipes 31 with the numerous small downwardly extending pipes 32 communicating with the transverse terminal 75 manifolds 33, which latter all communicate with the terminal header 34. The pipes 30 and 32 are preferably arranged, as indicated, in various groups, the ascending and descending pipes of a group being disposed at 80 different distances longitudinally of the manifolds 29 and 33, the pipes 31 connecting the different pipes of a group and extending diagonally from the upper ends of the pipes 30 to the upper ends of the pipes 32 of the 85 same group. The numerous pipes 30 and 32, and associated connections, are housed within the structure 35 open at its bottom and having at its top an open work cover 36 of wire mesh or the like, whereby air circulates freely around the condenser pipes for abstracting heat therefrom.

By arranging the pipes 31 diagonally it has been found that a better distribution of flow therethrough is secured, thus utilizing the entire cooling area of the condenser structure. With the pipes 31 each connecting a pipe 30 with that pipe 32 which is directly opposite, it was found that most of the fluid passed through those pipes nearest the 100 initial or intake header.

From the transverse manifolds 29 and 33

extend downwardly the several pipes 37 which communicate at their lower ends with a pipe 38, with which is connected the riser pipe 39 communicating through valve 40 with the still S at its top, this pipe structure constituting a runback, whereby there are returned into the still S those heavier oils whose vapors have been condensed in the air condenser and which have been only partially, if at all, subjected to the desired treatment.

There is connected with the header 34 of the air condenser a pipe 41, to which is connected the tell-tale pipe 42 controlled by valve 43. The pipe 41 communicates through the valve 44 and the pipe 45 with the intake of the pressure reducing valve 46, whose outlet communicates through the pipe 47 and valve 48 with the vapor line or pipe 49, which conducts away from the air cooled condenser structure the uncondensed vapors, those of lower boiling point oils. The pipes 41 and 49 are also connected through the normally closed by-pass valve 50.

The vapors of the heavier oils entering the condenser structure are condensed and returned to the still S through the runback connections 37, while the lighter vapors of the desired products are not condensed in the air condenser, but pass off through the reducing valve 46, the still S and condenser structure generally being under pressure, as for example, in the production of gasolene or light oils by cracking heavier oils. Uncondensed lighter vapors emerging from the reducing valve 46 are conducted off to a water cooled condenser, not shown, or to any other suitable device or desired destination.

What I claim is:

1. Condenser structure comprising initial and terminal manifolds, a header through which vapor may be supplied to said initial manifolds under pressure, upwardly extending and downwardly returning pipes connecting the said initial and terminal manifolds, and means for separately withdrawing from the terminal manifolds the gaseous and liquid products of condensation.

2. Condenser structure comprising initial and terminal manifolds, a header affording communication between the terminal manifolds, upwardly extending and downwardly returning pipes connecting the said initial and terminal manifolds, means for directing a flow of vapor through said pipes, and means for withdrawing the liquid and gaseous products of condensation from said terminal manifolds and header.

3. An oil vapor condenser comprising initial and terminal header pipes, initial and terminal manifolds connecting, respectively, with said initial and terminal header pipes,

and upwardly extending and downwardly returning vapor conducting pipes connecting said initial and terminal manifolds.

4. An oil vapor condenser comprising initial and terminal header pipes disposed at substantially the same level, initial and terminal manifolds connecting, respectively, with said initial and terminal header pipes, and upwardly extending and downwardly returning vapor conducting pipes connecting said initial and terminal manifold.

5. An oil vapor condenser comprising initial and terminal header pipes, initial and terminal manifolds connecting, respectively, with said initial and terminal header pipes, and upwardly extending and downwardly returning vapor conducting pipes connecting said initial and terminal manifolds, said vapor pipes disposed in groups, the upwardly extending parts of a group being disposed in different relative positions along the initial manifold from the longitudinal positions of the downwardly returning parts relative to the terminal manifold.

6. An oil vapor condenser comprising initial and terminal manifolds disposed substantially parallel with each other, groups of upwardly extending and downwardly returning vapor conducting pipes connecting said manifolds, the upwardly extending pipes of a group being disposed at a different relative position longitudinally of said manifolds from the relative position of the downwardly returning pipes of the associated group, and diagonally extending pipes connecting said pipes at their upper ends.

7. An oil vapor condenser comprising initial and terminal header pipes, initial and terminal manifolds connecting, respectively, with said initial and terminal header pipes, upwardly extending and downwardly returning vapor conducting pipes connecting said initial and terminal manifolds and vapor inlet and outlet connections connecting, respectively, with said initial and terminal header pipes.

8. A condenser for fractionating oil vapors under pressure comprising initial and terminal manifolds, upwardly extending and downwardly returning vapor conducting pipes connecting said manifolds, means for delivering oil vapors under pressure into an initial manifold, a pressure reducing valve, and a connection from a terminal manifold conducting uncondensed vapors to said reducing valve.

9. A condenser for fractionating oil vapors under pressure comprising initial and terminal manifolds, upwardly extending and downwardly returning vapor conducting pipes connecting said manifolds, means for delivering oil vapors under pressure into an initial manifold, a pressure reducing valve, a connection from a terminal mani-

- fold conducting uncondensed vapors to said reducing valve, and connections with said initial and terminal manifolds for drawing off condensed oil vapor.
10. A condenser for fractionating oil vapors under pressure comprising initial and terminal headers, initial and terminal manifolds connecting, respectively, with said initial and terminal headers, upwardly extending and downwardly returning vapor conducting pipes connecting said initial and terminal manifolds, means for conducting oil vapor under pressure into an initial header, a reducing valve, and a connection connecting with a terminal header and conducting uncondensed vapors to said reducing valve. 50
11. A condenser for fractionating oil vapors under pressure comprising initial and terminal headers, initial and terminal manifolds connecting, respectively, with said initial and terminal headers, upwardly extending and downwardly returning vapor conducting pipes connecting said initial and terminal manifolds, means for conducting oil vapor under pressure into an initial header, a reducing valve, and a connection connecting with a terminal header and conducting uncondensed vapors to said reducing valve. 55
20. 12. An oil vapor condenser comprising initial and terminal manifolds, upwardly extending and downwardly returning vapor conducting pipes connecting said manifolds, a header connecting one set of said manifolds, and connections with said initial and terminal manifolds for drawing off condensed oil vapor. 60
25. 13. A condenser comprising initial and terminal manifolds, a plurality of groups of upwardly extending and downwardly returning pipes connecting said manifolds, said groups occupying different positions longitudinally of the manifolds, and diagonally extending pipes connecting the upwardly extending pipes of a group to the downwardly returning pipes of the same group, said diagonally extending pipes of different groups crossing each other. 65
30. 14. Condenser structure comprising initial and terminal manifolds disposed in side-by-side relation and pipes connecting said manifolds, the said pipes being disposed diagonally of the said manifolds. 70
35. 15. Condenser structure comprising initial and terminal manifolds disposed in side-by-side relation and pipes connecting said manifolds, the pipes being arranged in groups and each group being composed of a series of pipes diagonally disposed with relation to the said manifolds and crossing the pipes of another group. 75
40. 16. Condenser structure comprising initial and terminal manifolds and pipes connecting said manifolds, some of said pipes being connected at one end to the initial manifold adjacent to the front end thereof and at the other end connected to the terminal manifold at a point remote from its ends and other ones of said pipes being connected to the initial manifold at a point intermediate its ends and extending across the first named pipes. 80
45. 17. Condenser structure comprising an initial manifold and a terminal manifold, a cooling passage extending from a point adjacent to one end of the initial manifold to a point remote from the ends of the terminal manifold, and a passage extending from a point remote from the ends of the initial manifold to a point adjacent to one end of the terminal manifold. 85

In testimony whereof I have hereunto affixed my signature this 26th day of Oct., 1920.

JOSEPH W. LEWIS.
